J. R. KIRLEY & H. B. WALKER,
WIRE LINE PUMPING OUTFIT FOR OIL WELLS,
APPLICATION FILED JAN. 7, 1916.

1,266,817.

Patented May 21, 1918.

FIG. 1

UNITED STATES PATENT OFFICE.

JOHN R. KIRLEY, OF MARIETTA, AND HENRY B. WALKER, OF LANCASTER, OHIO.

WIRE-LINE PUMPING OUTFIT FOR OIL-WELLS.

1,266,817.

Specification of Letters Patent.

Patented May 21, 1918.

Application filed January 7, 1916. Serial No. 70,863.

To all whom it may concern:

Be it known that we, JOHN R. KIRLEY and HENRY B. WALKER, citizens of the United States, residents of Marietta and Lancaster, respectively, in the county of Fairfield and county of Washington, respectively, and State of Ohio, have invented a new and useful Improvement in Wire-Line Pumping Outfits for Oil-Well; and we do hereby declare the following to be a full, clear, and exact description thereof.

Our invention relates to wire line pumping outfits for oil wells, its object being to provide a frangible joint adapted to be sheared where the pump becomes stuck within the pump barrel, and so provide for the easier withdrawal of the wire line and tubing.

These outfits are now employed in place of the old sucker rods connected by threaded joints, as they do away with the numerous sections required to be secured together in making up the pumping system. The wire 1 connected to the walking beam passes through a sliding joint 2 at the top of the well formed of a hollow sleeve of sufficient length for the pumping stroke and working in a suitable journal 3, and the wire extends down close to the location of the pump 4 where a few metal sections 5 are added to hold the wire line taut, below which is the pump working in the pumping barrel. The pumping barrel 6 is sustained at the base of the line of tubing 7, and below the same is the pump valve 8 placed above the strainer 9 located where the oil is collected within the oil bearing strata. In the pumping action grit or sand is liable to be carried up by the oil, and where the pumping of the oil is stopped for any reason, this sand or grit sometimes settles around the pump and within the pumping barrel and causes the same to stick fast and resist the entire power of the pumping engine. In such cases it is necessary to remove the tubing and pumping line and in case the wire line remains within the tubing, this is a very difficult, expensive and tedious operation requiring the frequent cutting of the wire line, the slipping of the sections of tubing over the wire line, etc., and often occupying as much as a week's time.

By the present invention, a frangible joint is provided at or near the base of the wire line, so that under a certain pulling strain, this joint will part and permit the

withdrawal of the wire line, permitting the withdrawal of the tubing itself separate from and independent of the wire line, which accordingly cheapens, facilitates and quickens the work.

In the accompanying drawing, Figure 1 is a sectional view of the well, showing the same in two separate sections; Fig. 2 is a side view of the frangible joint; Fig. 3 is a like view at right angles thereto; Fig. 4 is a longitudinal section, and Fig. 5 is a cross section.

The frangible joint 10 is preferably located near the base of the pumping line, for example, just above the pump 4. It is connected to the lower sectional weight and to the pump by a threaded pin and socket joint 11 and 12, and it is composed of a male member and a female member, these members fitting snugly with each other. The male member 13 has at its base the shoulder 14 and above the same the cylindrical body 15, while the female member has the sleeve 16 fitting over the cylindrical body and abutting against the shoulder 14 of the male member. The two members are provided with a series of rivet holes which register with each other, the male member having the rivet holes 18, and the sleeve member 19 having the rivet holes 19. Through these rivet holes the rivets 20 pass to hold the two sections against longitudinal separation, and the number and size of rivets employed depend upon the weight of the tubing and the force necessary to break the clamping grip and cause the shearing of the rivets. To this end, we prefer to employ rivets of great tensile strength, the drawing showing a series of larger rivet holes 18 and 19 and the rivets 20, and also a second series of like rivet holes 21 of smaller diameter, requiring smaller rivets. The sleeve 16 is slotted from its base to the end of its bore, as at 22, to provide for the clamping of the sleeve upon the male body portion by the upsetting of the rivets, forming in this way a clamping grip of the sleeve upon the telescoping portion of the male member, and one not liable to yield through vibration in pumping and shock, except under the recognized load for shear. For example, it is calculated that copper rivets of a larger size, when made properly, will stand a shearing strain of 2800 lbs. each, and if made of steel will stand a shearing strain of 3500 lbs. each. Thus, in making up the joints the number

and size of rivets to be employed and the character of the rivets can be ascertained according to the weight of the line of tubing, it being desired that the clamping grip of the sleeve be such as to prevent play between the parts and to sustain all ordinary pumping shocks and strains, and yet will yield before the strain is sufficient to raise the tubing in the well, this being a matter of calculation according to its depth, which usually varies from 1000 to 4000 feet.

When the invention is in use, the pumping operation is followed in the ordinary way, and the wire line is stretched by the weighted sections and the pump is raised and lowered within the pumping barrel, and the oil being drawn in through the strainer 9 is on the up stroke of the pump drawn through the valve 8 into the pumping barrel and on the down stroke passes upwardly through the pump 4 and is held above the pump within the tubing, being thus raised within the tubing by the pumping strokes. In this operation the frangible joint transmits the power without allowing any play of the parts, the base of the sleeve 16 fitting firmly against the shoulder 14 of the pump section 13, and the frangible joint therefore providing for positive transmission of the power on both the up and down strokes of the pump.

In case the pump becomes stuck in the pumping barrel, such, for example where the sand or grit is carried in with the oil and the pumping operation ceases so that this sand or grit will pack around the pump and stick it fast, the operator may overcome this condition by applying heavy power to the pumping line and start the pump; but if this proves impracticable, he applies sufficient force to cause the shearing of the rivets in the frangible joint, and so frees the wire line from the pump. In this operation the power to be applied is less than that required for the raising of the tube, else the frangible joint would not perform its function without anchoring down the tubing. According to the known weight of the line of tubing the number and character of rivets employed is fixed and when the power necessary to shear the rivets is applied, the wire line parts from the pump leaving it within the well. The wire line can then be easily withdrawn from the well, and the well tubing can also be easily and quickly withdrawn, separate and independent from the wire line, whereas the necessity of performing this operation with the wire line within the tubing, would necessitate the slipping of the tubing over the wire line or cutting of the wire line during the withdrawal of the tubing. The frangible joint can be arranged for re-use simply by the insertion of new rivets.

What we claim is:

65 1. The combination with a wire line

pumping outfit, of a telescopic frangible joint, each member of which has terminal abutment with the other, and a series of clamping rivets uniting them.

2. The combination with a wire line 70 pumping outfit, of a cylindrical telescopic joint, each member of which has terminal abutment with the other, and a series of frangible rivets uniting them, the rivets being adapted to be sheared under known 75 strains.

3. The combination with a wire line pumping outfit, of a cylindrical telescopic joint located therein and formed of male and female members, each having terminal 80 abutment with the other, the female member having a slot extending longitudinally the length of its bore, and one or more frangible clamping rivets for clamping the female member upon the male member, said 85 rivets adapted to shear under a predetermined load.

4. The combination of a line of well tubing carrying a pumping barrel at the bottom, a wire pumping line carrying a pump 90 at the bottom working within the pumping barrel, and a telescopic frangible compression joint between the wire and pump adapted to yield under a predetermined heavy strain.

5. The combination of a line of well tubing having a pumping barrel at the bottom, a wire pumping line carrying a pump operating within said barrel, and a telescopic joint between the pumping line and pump 100 formed of male and female members, each having terminal abutment with the other, and compression rivets transversely uniting the members adapted to shear under a load less than the weight of the tubing.

6. In a wire line pumping outfit for wells, the combination of the pump and wire line, and a telescopic frangible joint between them, said joint comprising members each having terminal abutment with the other, and having a series of rivet holes of different diameters registering with each other, and one or more compression rivets passing through one or more holes to clamp the sections together.

7. In a wire line pumping outfit for wells, the combination of a pump and a wire line, and a frangible joint between them, said joint comprising male and female members, each having terminal abutment with the other, said female member being adapted for compression upon the male member, and frangible rivets for compressing the female member for uniting the members.

8. In a wire line pumping outfit for wells, 125 the combination of a pump and a wire line, and a telescopic frangible joint between them, the sections of said joint being united by one or more compression rivets, said frangible joint being formed of a male member 130

having a body portion and a shoulder at the base thereof, and a female member having a sleeve fitting around the body portion, and contacting with the shoulder, and having its 5 bore terminating in a seat against which the end of the male member abuts.

In testimony whereof we, the said JOHN

R. KIRLEY and HENRY B. WALKER, have hereunto set our hands.

JOHN R. KIRLEY.

HENRY B. WALKER.
